UNITED STATES PATENT OFFICE.

HENRY C. HOPKINS, OF LITHONIA, GEORGIA, ASSIGNOR TO THE HOPKINS PNEUMATIC AUXILIARY ENGINE COMPANY, OF SAME PLACE.

LOCOMOTIVE.

SPECIFICATION forming part of Letters Patent No. 647,969, dated April 24, 1900.

Application filed May 23, 1898. Serial No. 681,508. (No model.)

To all whom it may concern:

Be it known that I, HENRY CALVIN HOPKINS, a citizen of the United States of America, and a resident of Lithonia, in the county 5 of De Kalb and State of Georgia, have invented certain new and useful Improvements in Locomotives; and I do hereby declare the following to be a full, clear, and exact description of the invention, such as will enable 10 others skilled in the art to which it appertains to make and use the same, reference being had to the accompanying drawings, and to letters and figures of reference marked thereon, which form part of this specification.

15 This invention relates to locomotives, having particular reference to providing means whereby the momentum or propulsion of the locomotive may be caused to store air for use in furnishing motive power to assist in the 20 propulsion of the train upgrades and wherever else necessary and for use in the air-brake system and any other purpose to which air might be applied on the engine or train.

To these ends the invention consists in the 25 device hereinafter fully specified, and shown in the accompanying drawings, in which—

Figure 1 is a side elevation of the device in running position. Fig. 2 is a sectional view on the line 2 2 of Fig. 4. Fig. 3 is a detail 30 view showing the relief and throttle valves. Fig. 4 is a sectional view on the line 4 4 of Fig. 2.

In the figures like reference characters are uniformly employed in the designation of corresponding elements of construction.

35 *a* represents the driving-wheels; *b*, the steam-cylinder and valve-chest; *c*, the valve-stem, and *d* the piston-rod. *e* is the main reservoir of the air-brake system, and *f* the tender. All of these elements may obviously 40 be constructed in any desired manner.

On the upper side of the cylinders *b*, and preferably on each side of the engine, are cylinders 45 10, which may, however, be secured to any portion of the locomotive adaptable to the purpose, said cylinder containing a piston suitable for operation, as the piston of a pump or an air-motor of the reciprocating class, 11 being the piston rod or stem thereof, and 12 being an arm by means of which said piston-rod 50 11 is connected operatively with the cross-head *d'*, as shown, or some other portion of the

piston-rod *d*, so that the reciprocation of the rod 11 may be in synchronism and coextensive with the reciprocating movement of the piston *d*. On the upper side of the cylinder 10 is a 55 valve-chest 13, which has thereon two chambers 14 and 15, Fig. 2, the former of which is arranged as a pump valve-chest—that is, having suitable ports 16, valves 17 of any desired construction, ports 18, controlled by valves 60 58, and the other common and well-known construction necessary to form the valves of a pump—while the chamber 15 has the usual ports 19, connecting it with the cylinder 10, and is provided with a slide-valve suitable to 65 control the admission and exhaust of compressed air to and from said cylinder 10. 20 is the valve-stem of said air-motor valve and is connected to the piston *c* of the steam-engine slide-valve by means of an arm 20', which 70 connects the two valve-rods together operatively, so that the reversal of one will reverse the other. Now it is obvious that with these valves, which will be called the "air-pump" 75 valves and "motor-valve," respectively, the cylinder 10 may be used as an air-pump or as an air-motor. Now in order to make these chests functionally interchangeable I connect the pipe 21 with the chamber 15, connecting them to the pipe 22 through the me- 80 dium of a three-way cock 23, which is operated by means of a lever 24 and a rod 25, ex- tending back to the cab, where it may have a lever 26 for manual operation. This three- 85 way cock operates, as just inferred, to open communication between the air-pump chest 14 and the pipe 22 and in a reverse direction between the pipe 22 and the air-motor casing 15. The pipe 22 extends from the valve 23 90 backwardly along the side of the locomotive to a suitable tank 27, which tank in the construction shown is placed upon the tender, although it may be of any desired shape and placed in any desired position. In order to connect the cylinder 10 on the opposite side 95 of the locomotive with pipe 22, the pipe 28 is employed, extending from the valve 23 of that side to a point intermediately between the relief and by-pass and the valve 23.

In the pipe 22 is a relief-valve 29, and 30 is 100 a pipe forming a by-pass around said relief-valve.

31 is a three-way cock, the lever of which is connected to a lever 33 within reach of the engineer by means of a rod 32, said three-way cock operating to open and close communication through the by-pass from end to end thereof or from either end of said by-pass to the open air through the nozzle 34, the relief-valve 29 acting to keep and limit the back pressure in the pipe 22 when the cylinder 10 is being used as a pump and the valve 31 is closed against the passage of air backwardly through the pipe 22 of the tank 27, all for a purpose hereinafter specified. This relief-valve 29 may be set to any desired tension, so that the back pressure may be constant at a predetermined necessary tension when the valve 31 is in the position just described. 35 is a triple valve such as are used in ordinary air-brake systems, although of a relatively-simple form, and is interposed in the connection between the pipe 22 and the auxiliary reservoir *e*, whereby when the pressure in the said auxiliary reservoir shall have become decreased below the working tension said triple valve will automatically restore said pressure from the pipe 22 in case the pressure in the pipe 22, and hence in the reservoir 27, shall be below the working pressure of the air-brake system the engineer by opening the three-way cock 36, so that air passes from the pipe 22 ahead of said cock to the pipe 37, leading from said cock 36 to the reservoir *e*, and the air-pump will cause it to pass directly to the reservoir, which may be continued until the pressure in said reservoir reaches the proper working pressure for the air-brake system, as indicated upon the dial of the pressure-gage 38.

The operation of this device is as follows: 40 Air may be pumped at any time through pipe 22 to the reservoir 27 and there stored for use by opening the valve 23, so that a passage is opened from the chamber 14, Fig. 2, through the pipe 21 to said pipe 22. This may be done by the surplus energy of the locomotive in moving upon levels or by its momentum and gravity in descending grades. The force required in pumping acts as a braking power due to the back pressure from the reservoir 45 27 and will assist in controlling the train on downgrades. If this is not sufficient back pressure for the purpose, the valve 31 will be closed and the air will be compelled to pass through the relief or pressure-retaining valve 50 29, which may be made by adjustment to hold back upon the pump with any desired pressure, all air above what is required to sustain that pressure passing through said retaining or relief valve to the reservoir 27. 55 Should the air-pressure in the reservoir 27 become too high at any time, it may be reduced by opening the valve 31, so that the surplus air will escape through the outlet 34 to said valve. When it is desired to run the pump 60 without forcing more air into said reservoir 27, the valve 31 will be so set as to open communication between the forward end of the

pipe 22 and the open air by means of the outlet 34. Now when it is desired to assist the steam-engine in propelling the locomotive the 70 valve 23 is set so that air may pass from the pipe 22 to the chamber 15 and may not pass through the pipe 21, when the air in the reservoir 27 will be utilized in actuating the cylinder 10.

Having thus described my invention, what I claim as new, and desire to secure by Letters Patent of the United States, is—

1. In a locomotive, an air-reservoir, a supplementary pair of cylinders and pistons, a set of pump-valves and ports and an engine-valve connected to each cylinder, and all connected and arranged to operate interchangeably.

2. In a locomotive, an engine consisting of 85 duplicate cylinders on each side, one cylinder on each side connected for using steam and the other cylinder on each side being provided with air-pump and air-motor valves and an air-reservoir, all connected to act conjunctively.

3. In a locomotive, a steam-engine comprising steam-cylinders, valves, pistons, their valves, valves and their rods and operating connections, an auxiliary air-cylinder for each 95 steam-cylinder, a piston and rod therefor, means for connecting said piston-rod with the piston-rod of the steam-cylinder, a valve controlling the admission and exhaust of air from said air-cylinder and means for connecting 100 said valve operatively with the steam-engine valve, and a source of air-pressure.

4. In a locomotive, steam-cylinders, piston and piston-rods, valves and valve-rods, an auxiliary cylinder near each steam-cylinder 105 a piston therein provided with a rod and means for connecting said rod with the steam-piston rod, a valve-chamber connected with said auxiliary cylinder a slide-valve therein, a stem for said slide-valve, an arm connecting said stem with the correlative valve-rod, a second chamber connected by ports to said cylinder, a set of pump-valves in said ports, a reservoir, a pipe leading from both valve-chambers thereto, and means for interchangeably connecting said valve-chambers thereto.

5. In a locomotive, steam-cylinders, piston and piston-rods, valves and valve-rods, an auxiliary cylinder near each steam-cylinder, a piston therein provided with a rod and 120 means for connecting said rod with the steam-piston rod, consisting of an arm connected to each of said rods rigidly a valve-chamber connected with said auxiliary cylinder a slide-valve therein, a stem for said slide-valve, 125 means for connecting said stem operatively with the correlative valve-rod, a second chamber connected by ports to said cylinder, a set of pump-valves in said ports, a reservoir, a pipe leading from both valve-chambers thereto, and means for interchangeably connecting said valve-chambers thereto.

6. The combination with a steam-motor of an air-pump actuated thereby, a reservoir, a

pipe connecting said pump and reservoir, a relief-valve in said pipe a by-pass around said relief-valve, and a valve governing said by-pass, for the purpose specified.

5 7. The combination with a steam-motor of an air-pump actuated thereby, a reservoir, a relief-valve in said pipe a by-pass around said relief-valve and a three-way valve governing said by-pass, and having an opening to the outer air for the purpose specified.

8. In a locomotive, an engine consisting of duplicate cylinders on each side, one cylinder on each side connected for using steam and the other cylinder on each side being provided

with air-pump and air-motor valves and an 15 air-reservoir, all connected to act conjunctively, a pipe leading from said air-pump-valve chamber, and another pipe leading from said air-motor-valve chamber, said pipes being joined in a three-way cock, and a pipe 20 leading from the third opening of said cock to said reservoir.

In testimony whereof I hereunto affix my signature in presence of two witnesses.

HENRY C. HOPKINS.
